UNITED STATES PATENT OFFICE.

HENRY B. COHEN, OF NEW YORK, N. Y., ASSIGNOR TO RAZOR PRODUCTS CORPORATION, OF LONG ISLAND CITY, NEW YORK, A CORPORATION OF NEW YORK.

STABILIZER FOR SAFETY-RAZOR BLADES.

Application filed March 5, 1925. Serial No. 13,070.

To all whom it may concern:

Be it known that I, HENRY B. COHEN, a citizen of the United States, residing at New York city, in the borough of Manhattan and State of New York, have invented certain new and useful Improvements in Stabilizers for Safety-Razor Blades, of which the following is a specification.

This invention relates to safety razors of the kind in which a relatively thin blade is held between a base and a cap, usually under conditions which curve the blade over the base, and by regulating the curvature or deflection of the edges of the blade, determine the shaving efficiency of the razor. This method of determining the position of the cutting edge of a safety razor blade is objectionable for the reason that it holds the blade between a bearing surface on the base and the impinging edge of the cap, which are spaced apart in the plane of the blade, and therefore render it impossible to stabilize or rigidly hold the edge of the blade except when the entire surface of the blade is clamped down tightly upon the curved surface of the base, and, therefore, in a position which defeats shaving efficiency. It has been proposed to obviate this difficulty by providing along the face impinging portion of the base, parallel with the comb, a channel or groove which lies beneath the impinging edge of the cap and therefore permits the cap to depress the edge over this groove while the inner wall of the groove serves as a fulcrum over which the blade is curved. But this construction is undesirable because of the weight of the base and the depression of the cutting edge to or below the plane of the comb.

Now, the object of the present invention is to provide means, in the form of a very light, inexpensive, and readily applied attachment, whereby existing safety razors of the kind having a continuous arcuate blade receiving surface, may be adapted to firmly grip the marginal portion of a thin razor blade between two superposed jaws which, while drawn tightly together and therefore adapted to hold the edge rigidly, or in other words stabilize the edge, will positively present the edge rigidly in a plane sufficiently removed from the facial surface of the comb as to accurately and without adjustment define the desired cutting efficiency of the razor. In other words,

the purpose is to equip each razor of the kind described so that it will give to the blade a predetermined set, rigid and free from chattering, by the mere act of drawing the base and cap together to the utmost 60 limit.

The invention proceeds upon the principle of applying to each marginal portion of the head or base of a razor, a member constituting a clamping jaw which, on the one hand, will have a dimension which accurately predetermines the spacing of the razor edge from the plane of the comb, and on the other hand coacts with the immediately superposed portion of the clamping cap to cause the blade to be rigidly gripped between the jaw and the cap and permit the cap to be drawn down to its ultimate limit, and thereby insure stability 70 of the edge of the blade without eliminating 75 the spacing of the edge requisite to shaving efficiency.

In the preferred embodiment of the invention, the clamping and spacing jaws are united in the form of a frame which not 80 only spaces the jaws apart to insure their proper relation to the combs of the base, but embraces the base laterally to resist displacement of the jaws in that direction while the blade and cap are being assembled 85 with the base, and, also preferably carries a pair of extensions which embrace the aligning pins of the cap or other elements which define the relation of the cap and base, and thereby determine the distance of 90 the spacing and clamping elements back from the combs.

In the accompanying drawing, in which two embodiments of the invention are shown by way of illustration—

Figures 1 and 2 are axial sections, in two planes at right angles to each other, of a known type of safety razor having one form of the invention applied thereto; Figure 3 is a section on the line 3^x—3^x of Figure 2; 100 Figure 4 is a perspective view of the attachment shown in Figures 1, 2, and 3; and Figure 5 is a view similar to Figure 4 showing a modified embodiment of the attachment.

1 represents the base of a known type of safety razor constructed with marginal combs 2, 3 represents a razor blade of the thin flexible type adapted to be supported on said base with its edges in position to be controlled in their shaving effect by the 110

combs 2, and 4 represents a cap adapted to be drawn to the base 1 by means of a sleeve 5 threaded upon the shank 6 of the cap 4. The cap 4 is provided with the usual aligning pins 7 which, like shank 6, pass through openings in the blade 3 and the base 1, thereby aligning the cap and blade with the base and insuring the proper relation of the cutting edges of the blade with the 10 combs 2.

The opposed faces of the base 1 and the cap 4 have customarily been formed on different arcs, the arc of the base being flatter than that of the opposed surface of the 15 cap. In razors of this type, the blade, being normally flat, is impinged by the outer edges of the cap and by inner portions of the base as the cap is drawn toward the base, so that the blade is flexed and the cutting 20 edges are depressed toward the facial surfaces of the combs, and the approach of the cap to the base is regulated by screwing the sleeve upon the shank until the resultant spacing of the edges of the combs give the 25 desired shaving efficiency; but inasmuch as this manipulation involved holding the blade between surfaces spaced apart, as distinguished from immediately superposed gripping faces, it resulted in an unstable 30 or chattering condition of the edge of the blade, particularly when increased spacing of the edges was desired.

Now, the present invention provides beneath the blade 3 a pair of combined spacing and gripping jaws 8 which are sufficiently near the combs 2 to enter into coaction with immediately superimposed portions 9 of the cap 4 and cause the blade 3 to be firmly gripped near enough to its cutting edges to stabilize the latter, and yet without the possibility of depressing the cutting edges more closely to the combs 2 than is permitted by the thickness of jaws 8, even though the cap be drawn down to 40 the extreme limit by means of the threaded sleeve 5. Thus, the thickness of the applied element 8, and not the degree of adjustment of the cap 4, determines the cutting efficiency of the razor. The elements 8 can, 45 of course, be made of any desired thickness.

In order to make the elements 8 very cheap and easily applied, and very accurate in their application, they are assembled in a frame-like structure, such as illustrated in 55 Figure 4 or Figure 5. In Figure 4, they are spaced apart and united in a pair by end bars 10 lying in the planes of the ends of the base 1 so as to snugly embrace the latter and resist displacement in the direction of their length; and said end bars 60 60 carry pin-engaging elements in the form of tangs 11 positioned to embrace the under surface of the base 1, thus preventing displacement of the jaws 8 upwardly with 65 reference to the base, and recessed as shown

at 12 to receive the pins 7 of the cap and thereby determine the distance of the jaws 8 inwardly from the combs 2 and prevent displacement of the attachment transversely of the base. 70

According to Figure 5, the attachment is formed of wire or other drawn material or stock of round or equivalent section, and embodies in its organization the spacing and clamping members or jaws 8^a adapted 75 to lie on the upper surface of the base 1, just as illustrated in the case of the jaws 8, the end members 10^a extending in the plane of the ends of the base 1 and across the same to the plane of the under surface 80 of the base, and the shanks 11^a positioned to embrace the under surface of the base and carrying eyes 12^a adapted to receive the pins 7. 85

Obviously, the invention may take other 85 forms and be constructed of other material than those here shown, so long as it involves the spacing and clamping jaws adapted to provide upstanding elements upon the upper face of the base, and means 90 for engaging the existing lines or elements of the razor for the purpose of positioning the attachment and locating the jaws appropriately to the functions which they are 95 to perform, as herein described. 95

I claim:

1. A blade stabilizing attachment for safety razors of the type employing a flexible blade clamped between a base and a cap; said attachment comprising spacing means constructed for interposition between the base of the razor and the blade to be mounted thereon, and to thereby elevate the blade upon the surface of the base; said spacing means having at its ends means for embracing the ends 105 of the razor base to prevent displacement thereon. 100

2. A stabilizing and spacing attachment for flexible blades of safety razors of the type employing a base and a cap confining the blade upon the base; said attachment comprising a pair of jaws adapted to overlie the surface of the razor base in position to support marginal portions of the blade from said surface and coat with superposed portions of the cap; said jaws being connected together by means extending beneath and embracing the razor base and defining their position thereon. 110 115

3. An attachment for safety razors of the type in which a flexible blade is confined between a base and a cap; said attachment comprising a pair of jaws adapted to overlie the surface of the base of such a razor and support the razor blade with its cutting 120 edges in a plane spaced therefrom, and end members connecting said jaws together and in position to underlie the ends of the razor base. 125

4. An attachment for safety razors of the 130

- type in which a flexible blade is confined between a base and a cap; said attachment comprising a pair of jaws adapted to overlie the surface of the base of such a razor and being constructed at their ends with means interlocking with a portion of the razor to 25 resist displacement of the attachment in the plane of the base.
- 5 support the razor blade with its cutting edges in a plane spaced therefrom, end members connecting said jaws together and in position to engage the ends of said base, and extensions on said end members in position 10 to engage beneath the base and resist lifting of the jaws from the latter.
5. An attachment for safety razors of the type in which a flexible blade is confined between a base and a cap; said attachment comprising a pair of jaws adapted to overlie the surface of the base of such a razor and support the razor blade with its cutting edges in a plane spaced therefrom, end members connecting said jaws together and in 15 position to engage the ends of said base, and extensions on said end members in position to engage beneath the base and resist lifting of the jaws from the latter; said extensions 20
6. In combination with a safety razor having a base, a cap coacting with the base to confine a flexible blade thereon, and aligning pins for positioning the cap relatively to the base; a blade stabilizing attachment comprising a pair of jaws constructed to overlie the surface of the base, end members uniting said jaws, spacing them apart, and engaging 35 the ends of the base to resist displacement of the attachment thereon, and extensions from said end members underlying the base and provided at their ends with means receiving the aligning pins of the razor to resist displacement of the attachment in the plane of the base. 40

Signed at Long Island City, L. I., New York, this 25th day of February, 1925.

HENRY B. COHEN.
